DESIGN FOR A DESK SET INKWELL

Robert A. May, Merion, and Harold E. Steinberg,
 Philadelphia, Pa., assignors to The Esterbrook
 Pen Company, Camden, N. J., a corporation of
 New Jersey

Application June 2, 1947, Serial No. 139,406

Term of patent 14 years

(Cl. D74—8)

To all whom it may concern:

Be it known that we, Robert A. May and Harold E. Steinberg, citizens of the United States of America and residents of Merion, Montgomery County, and of Philadelphia, Philadelphia County, both in the State of Pennsylvania, have invented the new, original, and ornamental Design for a Desk Set Inkwell, of which the following is a specification, reference being had to the accompanying drawing, forming part thereof, in which:

Figure 1 is a front perspective view of a desk set inkwell showing our new design;

Fig. 2 is a front elevational view of the same;

Fig. 3 is a rear elevational view;

Fig. 4 is a side elevational view, and

Fig. 5 is a plan view of the same on a reduced scale.

Our design for a desk set inkwell is characterized by the rounded contour at the front of the same whose surfaces diverge rearwardly from a median point and the inclined or beveled surfaces at the sides and rear; such diverging rounded front contour and beveled surfaces rising from a narrow rim at the base, together with

the stepped contours of the upper surface of the body disposed in a plurality of planes and extending over the rear wall surface in offset relation; such stepped portions having rounded contours at their front, with a dipping opening disposed at the axis of the rounded contours of such stepped portions, and a series of rounded bosses arranged in a circle substantially concentric with respect to the dipping opening.

We claim:

The ornamental design for a desk set inkwell, substantially as shown and described.

ROBERT A. MAY.
 HAROLD E. STEINBERG.
